UNITED STATES PATENT OFFICE.

LEON KNASTER, OF UNION CITY, NEW JERSEY.

CABINET DESK.

Application filed March 1, 1927. Serial No. 171,816.

This invention relates to a cabinet desk, and particularly to a construction including a secret container adapted to be concealed by a table member at the front of the desk and to be rendered conveniently accessible by a movement of such member.

In this character of desk it has been found particularly advantageous to locate the secret container or compartment in such position that it may be rendered accessible to the user of the desk when seated in front thereof and will not require the movement of the desk to obtain access to such a container.

It is further desirable that the container be associated with the table section of a desk and sufficient space provided for the withdrawal of the container from its compartment to permit access thereto without removing the container from the desk and this result is most effectively accomplished by the use of movable table sections. In the provision of such sections it is important to avoid friction and to shift the sections so that they may be supported by a withdrawn drawer which also controls a cover member for the cabinet portion of the desk which is normally accessible for use when the cover is opened.

To most efficiently accomplish this result the table section concealing the secret container has been pivoted at the front portion of the desk to swing outward from the container leaving a space for the withdrawal of the container, and this table section also carries a folding leaf which when in open position increases the area of the desk and when folded forms means in cooperation with the cover for locking the desk and table section when the drawer is closed.

The invention has for an object to provide a novel and improved construction of desk provided with a compartment opening toward the front and adapted to receive a secret container together with a pivoted table section at the front of said compartment and normally disposed to conceal the same in the public use of the desk.

A further object of the invention is to present a new construction of the concealing table section in which the section is pivoted at the front portion of the desk and normally supported to conceal a secret container at the rear thereof and this section is further provided with a folding leaf pivoted at the forward edge thereof and adapted in open position to extend the surface of the

desk while in its closed position it cooperates with a cover member actuated by the drawer of the desk.

A further object of the invention is to provide an improved construction of desk having a platform with a cabinet section above the same provided with a secret container at the upper surface of said platform and a drawer disposed beneath said platform, together with a table section pivoted at the front of the desk to conceal said container and adapted to cooperate with a cover for the cabinet section operatively connected to the drawer.

Other and further objects and advantages of the invention will be hereinafter set forth and the novel features thereof defined by the appended claims.

In the accompanying drawings:

Figure 1 is a perspective of the invention with the table section open for access to the secret container;

Figure 2 is a vertical section on the line 2-2 of Figure 1;

Figure 3 is a transverse vertical section with the parts indicated by full lines in closed position; and

Figure 4 is a detail section of the table sections.

Like reference characters designate corresponding parts throughout the several figures of the drawing.

This invention is adapted for application to any desired construction or configuration of desk, and is herein shown as applied to a cabinet desk particularly adapted for home use and in which a secret compartment is provided for the reception of private papers or other documents which it is desired to conceal from general accessibility but which can be conveniently reached by the user of the desk by simply swinging outward a section thereof.

In the application of the invention shown, the desk is provided with a platform 10 having a rear wall 11 and side walls 12, these being connected by the top 13. Extending between the side walls 12 is a public cabinet section 14 which may be provided with any desired arrangement of shelves or drawers as indicated in the drawings. Beneath this cabinet and resting upon the platform 10 a metallic compartment 15 is provided and is preferably of a fireproof nature so as to protect against destruction of the contents of the removable secret container 16 which

is slidingly mounted within the compartment 15. This container may be provided with any preferred locking means such as a combination lock, as indicated at 17, and in its outward movement is adapted to travel upon tracks or ways 18 resting upon the platform 10.

The cabinet section of the desk is provided with an arcuate cover member 19 which is slidingly mounted in the usual manner and connected at its rear with an operating arm or lever 20 which is pivoted at its lower end 21 to the rear of a drawer 22 disposed beneath the platform of the desk. This drawer is disposed to slide in suitable ways 23 secured to the side walls 12 of the desk and the front panel 24 of the drawer is extended upward at 25 above the top of the drawer walls and there engages a cross strip or stop 26 secured to the under face of the platform 10 and forming an abutment to limit the inward movement of the drawer. This drawer is preferably provided with locking means as indicated at 27 so that when the drawer is in closed position the cover and other members of the desk are completely locked.

For the purpose of concealing the secret container 16 a table section 28 is pivotally mounted at its front edge 29 upon the side walls of the forward portion of the desk and in its closed position is supported upon suitable rests or strips 30 so as to lie in alignment with the lower portion of the public cabinet section 14 and completely conceal the secret compartment 16 beneath the same. For the purpose of extending the desk section a folding leaf 31 is pivotally secured thereto by the hinge connection 32 at the front of the table section and this leaf when folded upon the table section fits closely between the side walls 33 so as to prevent any accessibility or raising of these sections when closed. Under some conditions it may be found desirable to frictionally retain the table section 28 in its closed position and for that purpose a spring retainer 34 may be mounted thereon to engage the side walls 33 of the front of the desk. Likewise, in order to permit the lifting of the table section to secure accessibility to the secret compartment a hand hold 35 may be mounted thereon, preferably in a recessed portion 36 which permits the close folding of the leaf 31 upon the table section. When either the table section or its folding leaf is extended beyond the front of the desk it is adapted to be supported by the front panel 24 of the drawer, as indicated by dotted lines in Figure 3, and to prevent marring or injury to the finished surface of these sections a felt bearing 37 is provided at the upper edge of the drawer front.

In the operation of the desk the cover for the cabinet section is opened by the with-

drawal of the drawer and the table leaf thus released and folded outward into contact with the upper edge of the drawer. The desk is then in condition for normal use with the secret compartment concealed but if it be desired to obtain access to this compartment the table section is bodily swung outward and lies upon the previously opened leaf which provides an open space permitting the complete withdrawal of the container so that access can be obtained to the contents thereof without the necessity of removing the container from the desk. When the desk is not in use the table section and its leaf are folded inward and the closing of the drawer brings the cover member of the cabinet into contact with these sections so that when the desk drawer is locked any access to the desk by unauthorized persons is prevented.

The invention therefore presents a simple, efficient, and economically constructed cabinet desk in which the concealing members for the secret container are so mounted as to be operable with the minimum of friction and provide a space while supported in extended position into which the secret container may be withdrawn for access thereto.

While the specific construction of the invention has been herein shown and described, it is not confined thereto as changes and alterations may be made without departing from the spirit of the invention as defined by the following claims.

Having thus described my invention, what I claim as new and desire to secure by Letters Patent of the United States, is:—

1. A desk provided with a compartment opening toward the front, a pivoted table section mounted upon the desk at the front of said compartment to normally conceal the same and adapted to swing into a position to permit access to the compartment, a cabinet portion above said compartment, a cover for said portion disposed to retain the table section when the cabinet is closed, a drawer mounted in the desk beneath said compartment, and an operating connection between said drawer and cover.

2. A desk including a platform, a public cabinet supported above the same, a metallic compartment disposed between said cabinet and platform, a secret container disposed in said compartment and adapted to be withdrawn toward the front of the desk, a table section pivoted at the front of the desk and supported to normally conceal said retainer, and guide members provided upon the upper surface of said platform to cooperate with said container when withdrawn.

3. A desk including a platform, a public cabinet supported above the same, a metallic compartment disposed between said cabinet and platform, a secret container disposed in said compartment and adapted to be with- 130

drawn toward the front of the desk, a table section pivoted at the front of the desk and supported to normally conceal said retainer, a stop provided at the front portion of the under face of said platform, a drawer having its front panel extended to engage said stop and limit the inward movement of the drawer and a movable cover for the cabinet connected to said drawer and adapted to engage the table section when closed.

4. In a desk, a platform, a public cabinet section disposed above the same, a secret container intermediate said cabinet and platform and withdrawable toward the front of the desk, means at the forward portion of the desk for concealing said container and movable to permit access thereto, a cover for the cabinet section cooperating with the concealing means, a drawer beneath said

platform connected to said cover and provided with an extended front panel, and means upon the platform to engage said panel for limiting the inward movement of said drawer.

5. In a desk, a body portion having a cabinet section, a secret container disposed in said section and adapted to open toward the front of the desk, a movable table section having a folding member disposed to conceal said container and operable to permit access thereto, and a cover for said cabinet mounted upon the body portion and adapted to engage the foldable member of the table section to prevent movement thereof when folded.

In testimony whereof I affix my signature.

LEON KNASTER.
